UNITED STATES PATENT OFFICE.

CHARLES BAULK, OF BRIDGNORTH, ENGLAND.

APPLIANCE FOR LUBRICATING THE PILE WIRES EMPLOYED IN JACQUARD AND LIKE LOOMS FOR WEAVING CARPETS, RUGS, OR OTHER LIKE FABRICS.

Application filed October 29, 1923. Serial No. 671,430.

To all whom it may concern:

Be it known that I, CHARLES BAULK, a subject of the King of Great Britain, residing at Bridgnorth, in the county of Salop, England, have invented certain new and useful Improvements in Appliances for Lubricating the Pile Wires Employed in Jacquard and like Looms for Weaving Carpets, Rugs, or Other like Fabrics, of which the following is a specification.

This invention relates to an appliance for lubricating the wires used in forming the loops or pile of carpets, rugs, and the like fabrics made on Jacquard and other like looms, the said wires being lubricated as they are pulled out of the loops forming the carpet or other fabric and then again introduced between the yarn and warp for the purpose of forming other loops. The present appliance is of simple construction enabling the wires to be lubricated all round and providing for an even wear upon the lubricating element; and furthermore, preventing dust or flights becoming deposited on the latter such as detract from proper functioning.

The invention comprises a roller brush adapted to be carried in one direction so as to peripherally bear against the lubricant and in the other direction against the pile wires and simultaneously having an intermittent rotary motion. The brush is moreover, capable of an axial traverse during its step-by-step rotation.

The appliance will be described with reference to the accompanying drawings.

Fig. 1 is a front view of the appliance constructed according to this invention, showing the roller brush in the upper normal position for lubricating the wires.

Fig. 2 is a central vertical section of Fig. 1.

Fig. 3 is a front elevation showing the roller brush after being swung down into contact with the lubricant.

Fig. 4 represents a front elevation of one side of a loom, showing the means whereby the pile wires are drawn out of the carpet and the improved appliance for lubricating said wires.

Fig. 5 is an alternative form of ratchet device whereby the roller brush is intermittently rotated as it is swung upwards towards the wires.

In carrying the invention into practice,

the appliance comprises a tubular case 1 of square, cylindrical, or other suitable shape, open at the upper and lower ends, in which is placed a solid lubricant 2, such as paraffin wax. The solid lubricant 2 is contained in a socket or holder 3 to which are attached cords 4 passing round upper pulleys and descending to a suitable weight 5 whereby the solid lubricant is kept up to its work as hereafter described. The case 1 is attached to a bracket 6 on which is fulcrumed a bell-crank lever 7, a circular roller brush 8 being rotatably mounted on a spindle 9 fixed in the arm 7^a of the bell-crank lever 7. Upon one face of the roller brush 8 is a ratchet wheel 10 with which engages an actuating pawl 11 connected to the bracket 6, and to the brush-carrying arm 7^a of the bell-crank lever is connected a detent 12 which engages the ratchet wheel 10 and prevents back rotation of the roller brush. The latter is disposed in the same vertical plane as the case 1 and above same in such manner that the lower peripheral edge of the brush lies opposite the orifice 80 of the case. A contractile spring 13 anchored from the bracket 6 is connected to the depending or free arm of the bell-crank lever 7 whereby the roller brush is normally held in the upper operative position against the pile wires 14.

The spindle 9 of the roller brush has a rear head or flange 15 which is bevelled on its inner side and engages a central bevelled face 16 on the inner wall of the central drum 8^a of the roller brush 8. This gives an effect that as the roller brush is rotated, it is capable of an axial traverse along its spindle 9 for a purpose hereafter described.

In the alternative form shown in Fig. 5, 95 the intermittent rotation of the brush 8 is effected when the same is swung upwards towards the wires, the hook-ended cam 11^a engaging with the teeth of the ratchet wheel 10 and causing the brush to be revolved in 100 an opposite direction to that aforesaid.

The roller brush is built up of bristles connected to the central drum 8^a and assembled between opposite side cheeks 17 and 18, the side cheek 17 connected by 105 screws 19 to the said drum being removable so that as the brush becomes worn, it can be replaced.

The appliance may be connected to a loom in any suitable manner.

The appliance may be tripped into the lower position against the lubricant by providing on a driving shaft 20, a cam 21, engaging an arm 22 fulcrumed at 23 to the loom frame, the upper end of the arm being connected through a rod 24 with the depending arm of the lever 7. Any other suitable means may be employed as will be understood.

10 In practice, with the form shown in Figs. 1 to 4, the solid lubricant 2 is maintained at the upper part of the case 1 so as to slightly project therefrom. As the wires 14 are pulled out of the loops or pile of the carpet, preparatory to being again introduced between the yarn and warp for the purpose of forming other loops, each wire is passed through the upper side of the brush and becomes lubricated all round. Before the wire is moved in a lateral direction at the end of its longitudinal traverse, upon the shaft 20 being rotated, the cam 21 moves the arm 22 in the direction of the arrow and through the rod 24 and lever 7 causing the brush to swing downwards out of contact with the wires but into engagement with the lubricant, at the same time, the roller brush is rotated by the pawl and ratchet means, thereby bringing different parts of the brush in turn with the lubricant and with the wires. Simultaneously, the rotary movement of the brush causes it to have a slight axial traverse along its spindle by means of its internal bevel face 16 engaging with the bevel head 15 of the spindle, thus preventing grooving of the brush and enabling a uniform wear of the same.

The rotary movement of the brush in the case of the form shown in Fig. 5 is effected when it is being swung upwards.

What I do claim as my invention, and desire to secure by Letters Patent, is:

1. An appliance for lubricating pile wires of looms, comprising a holder for lubricant, a bracket upon the holder, an arm fulcrumed to the bracket, a roller brush rotatably mounted in the arm, and means for causing said brush to peripherally engage with the lubricant.

2. An appliance for lubricating pile wires of looms, comprising a lubricant holder, a bracket projecting from the holder, a bell-crank lever fulcrumed to the bracket, a

roller brush journaled in the lever and peripherally opposed to the lubricant, a ratchet device connected with the roller brush, means for maintaining the roller brush in engagement with the pile wires, and means for swinging the brush into engagement with the lubricant.

3. An appliance for lubricating pile wires of looms, comprising a holder for lubricant, a bracket from the holder, an arm fulcrumed to the bracket, a roller brush rotatably mounted in the arm, a ratchet device connected with the roller brush, and means for causing axial movement of the brush as it is intermittently rotated.

4. An appliance for lubricating pile wires of looms, comprising a lubricant holder, a roller brush swingably carried and peripherally disposed opposite the lubricant, said roller brush having intermittent rotation as it is swung towards or from the lubricant, a resilient medium anchored to the lubricant holder and connected to the free arm of the bell-crank lever, and means connected to said free arm for swinging the brush against the lubricant.

5. An appliance for lubricating pile wires of looms, comprising a lubricant holder, an arm pivotally carried from the holder, a roller brush journaled in the arm and peripherally disposed opposite the lubricant, a ratchet wheel at one side of the roller brush, said roller brush having an intermittent rotation as it is swung in one direction, and being provided with an internal bevelled face, and a roller brush spindle with a bevelled head adapted to engage the bevelled face of the roller brush.

6. An appliance for lubricating pile wires of looms, comprising a lubricant holder, a bell-crank lever pivotally carried from the lubricant holder, a roller brush journaled in one arm of the bell-crank lever, a spring anchored to said holder and connected to the free arm of the bell-crank lever, a rod connected to said free arm of the bell-crank lever, an arm fulcrumed to the loom and jointly connected with the rod, and a cam engaging the arm, the roller brush having intermittent rotation as it is tripped out of normal position.

In testimony whereof I affix my signature.

CHARLES BAULK.
